CLAIM

The ornamental design for a docking device for fixation device for medical optical fiber, as shown and described.

DESCRIPTION

FIG. 1 is a perspective view showing our design;
FIG. 2 is a front elevational view thereof;
FIG. 3 is a rear elevational view thereof;
FIG. 4 is a right side elevational view thereof;
FIG. 5 is a left side elevational view thereof;
FIG. 6 is a top plan view thereof; and,
FIG. 7 is a bottom plan view thereof.

The broken lines depict portions of the docking device for fixation device for medical optical fiber that form no part of the claimed design.
